[57] ABSTRACT

Equipment for use in practising putting comprises a frusto-conical cup pivoted to a stirrup for movement about a horizontal axis and the stirrup is pivoted to a base for movement about a vertical axis. One end of the cup normally rests on the ground so that a golf ball can be projected into it. The other end of the cup includes circumferentially spaced members which extend into the path of ball putted into the cup to arrest same, but allow the egress of the ball if it is traveling at too great a velocity.

FIG. 5.

PRACTICE PUTTING DEVICE

This invention relates to golfing equipment, and it is an object of the invention to provide golfing equipment which can be used for both practising putting and for playing a putting game.

According to the invention golfing equipment comprises a receiver which is open at one end to enable it to receive a golf ball, a stirrup having pivot means for mounting the receiver for pivotal movement relative to the stirrup about a generally horizontal axis and mounting means enabling the stirrup to swivel about a substantially vertical axis, the pivot means for mounting the receiver being so arranged that, in use, the receiver is biased into a position in which one end thereof rests on the ground whereas, when a golf ball is projected into the receiver, the receiver will move about its pivot axis so that said one end moves clear of the ground.

The receiver is preferably in the form of a generally frusto-conical cup which is open at both ends, the pivot axis about which the cup moves relative to the stirrup being nearer the smaller diameter end of the cup than the larger end thereof. At said smaller diameter end, a series of inwardly directed projections are conveniently provided within the cup and are so dimensioned that, if a golf ball is projected into the cup at a velocity greater than a predetermined velocity, the golf ball will pass through the space defined by said projections whereas, if the velocity of the ball is less than said predetermined velocity, the ball will be retained by the projections and will remain in the cup.

The stirrup and cup are preferably formed as mouldings of a synthetic plastics material and the mounting means for the stirrup preferably comprises, for outdoor use, a spike or like element adapted to be driven into the ground, the spike being provided at its upper end with means for cooperation with part of the stirrup whereby the spike can be attached to the stirrup in such manner as to permit the stirrup to swivel freely about a vertical axis relative to the spike. The spike may thus be formed at its upper end with a cylindrical socket adapted to receive said part of the stirrup which is conveniently of stepped cylindrical form. The spike is preferably designed so as to have snap-fitting engagement with said cylindrical part of the stirrup.

In an alternative arrangement, wherein the equipment is intended for use indoors, the mounting means for the stirrup includes a flat plate of, for example, steel and the plate is provided with a socket which corresponds to, and is of substantially the same dimensions as, the socket of the spike.

The invention will now be described by way of example with reference to the accompanying drawings in which:

FIG. 1 is a side view of equipment for use outdoors in practising putting,

FIG. 2 is a plan view of the equipment shown in FIG. 1,

FIG. 3 is an end view of the equipment,

FIG. 4 is a detail view showing the method of attachment of two parts of the equipment and

FIG. 5 is a detail view showing a base plate to which the stirrup can be attached to enable one to use the equipment indoors.

As shown in the drawings, the equipment for outdoor use comprises a spike 10, a stirrup 11 which is arranged to swivel relative to the spike 10 about a vertical axis

and a receiver 12 in the form of a cup which pivots relative to the stirrup 11 about a horizontal axis. The receiver 12 is formed as a one-piece moulding from a synthetic plastics material such as polypropylene and is of slightly tapering form from one end 13 towards the other end 14 thereof. The receiver 12 is provided with external reinforcing ribs 15 formed integrally with stub shafts 16 which provide pins for the pivotal mounting of the receiver. The spike 10 and stirrup 11 are also formed as one-piece plastics mouldings.

The shafts 16 have snap-fit engagements with bifurcated end portions 17 of the arms of the stirrup 11, the shafts 16 being free to rotate within the bearing means afforded by the end portions 17 and the shafts being disposed nearer to end 14 of the receiver than to end 13 thereof. This means that the receiver 12 is normally biased gravitationally into the position shown in full lines in FIG. 1. In this position the lip of the receiver rests on the ground so that, when a golf ball is projected in the correct direction towards the receiver, the ball will enter the receiver.

Inwardly directed projections 18 (see particularly FIG. 3) are provided at end 14 of the receiver 12 and the purpose of these projections is to arrest any golf balls which enter the receiver with less than a predetermined momentum. If, however, a golf ball is given a considerable impact, the ball will travel past the projections 18 without being arrested thereby.

The arms of the stirrup 11 are of cranked form as can be seen from FIG. 3 and the base 19 of the stirrup is moulded integrally with a downward extension 20 of stepped cylindrical form, the lower portion of the extension 20 being split so as to provide, in effect, a plurality of depending fingers. This portion of the extension 20 fits into a socket 21 of the spike 10, the base of the socket 21 being preferably slightly undercut to provide a circumferential recess in which outward formations of said fingers can be received. The stirrup 11 thus has a snap-fit engagement with the spike 10. The bore of the socket 21 is enlarged at its upper end to provide a horizontal bearing surface 22 on which the step of the extension 20 is supported. The weight of the stirrup 11 and receiver 12 is transmitted to the spike 10 through the surface of the step and said surface 22 but the dimensions thereof are such that the frictional and load-derived forces acting between the surfaces do not prevent free rotation of the stirrup 11 about a vertical axis relative to the spike 10.

In use of the equipment, the spike 10 is driven into the ground so that a downwardly directed surface 23 thereof is at ground level, the receiver 12 tilts gravitationally into position in which the lip of the receiver at end 13 thereof rests on the ground and the receiver 12 and stirrup 11 are pivoted about a vertical axis relative to the spike 10 so that the central axis of the receiver is aligned with the direction in which it is intended that a golf ball will be hit. The ball is then putted towards the receiver and, if the direction in which the ball is travelling is correct, the ball will enter the receiver. If the ball is not putted in the correct direction it will either miss the receiver 12 completely or strike the rim thereof without entering the receiver.

If the velocity at which the ball is projected is excessive, the ball will travel past the projections 18 out of the receiver whereas, if the ball is projecting at an insufficient velocity, it will roll into the receiver and then roll out again. The object of the exercise is, of course,

to putt the ball at such velocity that it enters the receiver 12, travels within the receiver into engagement with the projections 18 so that the weight of the ball causes the receiver to pivot about the common axis of the shafts 16 and the ball is retained within the receiver. A putt which has the above effect is considered to simulate a successful putt in a game of golf.

The base plate 24 shown in FIG. 5 is intended to be used for indoor practising, the base plate 24 being made of iron or other metal and having a socket 25 in which the stepped cylindrical extension 20 of the stirrup 11 is fitted in such manner as to enable the stirrup 11 to pivot freely relative to the base plate 24.

I claim:

1. Golfing equipment comprising a receiver which is open at one end to enable it to receive a golf ball, a stirrup having pivot means for mounting the receiver for pivotal movement relative to the stirrup about a generally horizontal axis, and mounting means enabling the stirrup to swivel about a substantially vertical axis, the configuration of the receiver and the disposition of the axis about which the receiver pivots relative to the stirrup being such that the receiver is normally biased into an inclined position in which the lip of the receiver at said one end is in the same place as the path of a ball 25

projected towards the receiver, the receiver being arranged to pivot in response to passage of a ball into the receiver and beyond said pivot axis into a position in which the other end of the receiver is at a lower level than said one end, said other end of the receiver being substantially open and circumferentially spaced projecting means being provided at said other end to arrest a ball travelling with a velocity less than a predetermined velocity whilst allowing a ball travelling with a 10 velocity greater than said predetermined velocity to pass therethrough.

2. Golfing equipment according to claim 1, wherein there are four projections constituting said projecting means and wherein two of said projections are disposed at one horizontal level and the other two projections are disposed at another horizontal level.

3. Golfing equipment according to claim 1, wherein the mounting means comprises a spike adapted, in use, to be driven into the ground, the spike being provided at its upper end with a socket and stirrup including a portion of stepped cylindrical form which includes a part which has a snap-fit engagement in the socket and a part which rests on a load-transmitting surface surrounding the socket.
